ALIGNING FIXTURE

Roland Smith Payne, Salt Lake City, Utah, assignor to Remington Arms Company, Inc., Bridgeport, Conn., a corporation of Delaware

Application October 6, 1942, Serial No. 461,017

11 Claims.

(Cl. 33—181)

The present invention relates to an alignment gauge, particularly for axially aligning cooperative tools, as a punch with respect to a work-holding die and mandrel, wherein it is of extreme importance that the pocket formation produced by the punch and the displaced and compressed metal surrounding such formation be of exact concentricity. The invention is especially adapted to, and the present disclosure is illustrated in connection with, a punch and die employed in the manufacture of cartridge cases for the purpose of forming a primer cap receiving pocket centrally in the head end of the cartridge case. Perfect axial alignment of the punch and die is important both in connection with the production of a perfect cartridge case, wherein the primer cap pocket must be exactly centralized and the surrounding metal must be of uniform dimension and consistency, and in eliminating lateral strain on the punch, which results when the punch is not centralized and a smaller thickness of metal is confined between the punch and die at one side, and which strain causes excessive wear and frequent breakage of the punch. Also, where there are subsequent operations on the cartridge case accurate alignment at the pocketing operation adds greatly to obtaining maximum production and a reduction in tool wear and breakage in such subsequent operations.

In the particular form of punch and die contemplated, the pocket forming portion of the punch, in the form of a projecting teat, directly engages the head end of the cartridge case with the ejecting stem or mandrel supporting the cartridge case forming an anvil to cooperate with the punch, the punch having no direct engagement with the die opening in which the cartridge case is supported. It is consequently impossible to centralize the punch by directly engaging it with the die, and it has therefore been necessary in order to determine the alignment of the punch and die to operate the machine with a cartridge case in place with the result that the punch was apt to become damaged before actually going into production use.

It is an object of the invention to provide a device in the nature of a jig which may be fitted into relation with the punch and die prior to operation of the machine with the cartridge case in place, and without the necessity for directly engaging the punch with the die, so that the chance of premature damage to the punch or die due to misalignment is prevented. To this end, it is particularly proposed to provide a jig consisting of two main parts having registering

peripheral surfaces which are normally aligned, and including means upon one part adapted to be fitted in exact centralized relation in the die or die-holder, and means centralized with respect to the other part and adapted to receive the pocket forming teat of the punch in centralized relation, the two parts of the device being transversely shiftable with respect to each other, so that any misalignment between the punch and the die will result in a relative shifting between the two parts of the device, and hence will cause their normally registering peripheral surfaces to become out of register.

A further object is to provide a centering device in which the relatively movable parts are free to shift as the punch is transversely adjusted, so that upon perfect centralization of the punch the normally registering parts of the device will be in perfect register. Another object is to provide in one embodiment of the invention spring projected punch and die engaging parts adapted to automatically insure firm axial engagement of the device in perfect parallelism.

It is further proposed to provide such device wherein the perfect register of the two parts may be accurately determined by feel, as for instance, by moving the finger or fingernail across the joint between the two parts and determining by the absence of any projection of one part with respect to the other that the punch is properly aligned axially with the die.

With the above and other objects in view, embodiments of the invention are shown in the accompanying drawings, and these embodiments will be hereinafter more fully described with reference thereto, and the invention will be finally pointed out in the claims.

In the drawings:

Fig. 1 is a vertical longitudinal sectional view showing a punch and die of the type adapted to be axially aligned by means of the device of the invention, the punch being shown in separated relation to the die and the head end of the cartridge case being shown upon the reciprocating ejecting stem or mandrel at an intermediate position of its movement toward the punch moving to meet it.

Fig. 2 is a similar view, showing the punch engaged with the die at the completion of the pocket forming operation.

Fig. 3 is a side elevation of the aligning gauge, according to one illustrated exemplary embodiment of the invention.

Fig. 4 is an end elevation, showing the punch engaging end.

Fig. 5 is an end elevation, showing the die-engaging end.

Fig. 6 is a vertical longitudinal sectional view, taken along the line 6—6 of Fig. 5 and showing the gauge in its operative position in cooperation with the punch and die, the dot-and-dash lines indicating the position to which the punch engaging part shifts in respect to the die engaging part in the event of axial misalignment.

Fig. 7 is a side elevation of a modified form of the invention.

Fig. 8 is an end elevation, showing the punch engaging end.

Fig. 9 is a vertical longitudinal sectional view, taken along the line 9—9 of Fig. 8.

Fig. 10 is an end elevation, showing the punch engaging end, wherein the punch engaging member of the device is transversely shifted into axially disaligned relation to the die engaging member of the gauge.

Fig. 11 is a vertical longitudinal sectional view, showing the modified form of the invention illustrated in Figs. 7 to 10 in its operative position in cooperation with the punch and die holder.

Similar reference characters indicate corresponding parts throughout the several figures of the drawings.

Referring to the drawings, the aligning gauge, according to the exemplary embodiment of the invention illustrated in Figs. 1 to 6, is especially adapted for the axial aligning or centering of a punch with respect to a die in which a work-piece is moved into punch-engaging position by means of an ejecting stem or mandrel.

In Figs. 1 and 2 there is illustrated a type of punch and die for producing a primer cap pocket in the head end of a cartridge case, and wherein the cylindrical fixed die 10 removably secured in the cylindrical passage 11 of a fixed die-holder 12 is provided with a horizontal cylindrical passage 13, within which an ejecting stem or a mandrel 14, tapered at its forward end, reciprocates to feed a cartridge case 15 forwardly to bring its head end flush with the forward face of the die. The reciprocating pocket forming punch 16 is secured in the passage 17 of the reciprocating carriage part 18 of the machine, the punch being transversely adjustable relatively to the die by suitable known means. The punch includes a flanged forward end portion 19, preferably of larger diameter than the die passage 13, and a centrally disposed pocket forming teat projection 20 adapted to engage the head end of the cartridge case within the passage 12 to produce a central primer cap pocket therein. The reciprocation of the mandrel 14 is so synchronized with the reciprocation of the punch that the mandrel acts as a fixed anvil to support the closed or head end of the cartridge case at that instant when the projection 20 of the punch strikes the outside of the head end, the teat projection 20 of the punch thereupon impressing itself into the head of the cartridge case while opposed by the anvil forming mandrel to form the primer cap receiving pocket 21 in the cartridge case, as shown in Fig. 2.

It is obvious from the illustration in Fig. 2 that any axial misalignment between the die and the punch will not only cause an uneven strain upon the punch, but will produce a cartridge head in which the annular area of metal surrounding the pocket 21 is uneven both in dimension and consistency, and any such unevenness results in a dangerously defective cartridge case. The production of such cartridge cases is very rapid and

the punch must be renewed as soon as it shows wear. The aligning gauge of the present invention is especially adapted to permit of the quick and convenient aligning of replacement punches.

5 The aligning gauge comprises a cylindrical block member 22 provided centrally with a cylindrical passage 23 in its outer face and a larger diameter cylindrical chamber 24 extending from the passage 23 to the inner face. Diametrically at each side of the chamber 24 the block member is provided with threaded holes 25—25 adapted to receive post members, presently to be more fully referred to, and diametrically at each side of the passage 24 and centrally between the 10 threaded holes 25—25 there are provided bolt-receiving holes 26—26 at the inner face of the block having counterbored passages 27—27 extending to the outer side of the block. Headed bolts 28—28 are engaged in the holes 26—26 and 15 screwed into threaded screw-holes 29—29 in a cylindrical plate member 30 corresponding in diameter to the block member and concentric thereto and constituting a closure base for the cylindrical chamber 24. The block member 22 20 and the plate 30 are accurately positioned with respect to each other by means of dowels 31—31 engaged in dowel pockets respectively provided in the block and plate members. The plate member 30 is provided in axial alignment with the 25 threaded holes 25 of the block 22 with cylindrical holes 32—32 through which extend the post members, presently more fully referred to. The outer face of the plate member 30 is provided centrally with a dished recess 33, the annular rim 30 35 surface surrounding this dished recess being precisely ground to a flat finish to provide a flat sliding seat for the disc member of the device, presently to be more fully referred to.

Within the central passage 23 of the block member there is slidably engaged a cylindrical punch-engaging member 34 provided centrally with a precisely centered cylindrical hole 35, having an annular beveled seat surface 35^a at its outer end, upon which the rounded teat projection 20 of the punch is adapted to seat in centralized relation, as shown clearly in Fig. 6. The inner end of this hole 35 extends to an enlarged diameter spring engaging pocket 36 within which is engaged a helical spring 37, seating at one end 40 against the beveled end of the pocket and at its other end upon the closure plate member 30. Within the cylindrical chamber 24, the member 34 is provided with an outwardly projecting cylindrical flange 38 slidable in the chamber and 45 normally abutting the shouldered end of the chamber adjacent the passage 23 under the pressure of the spring to limit the projection of the member 34. An annular corner clearance recess 39 is provided at the end of the member 34 adjacent the flange 38. The spring mounting of the member 34 permits the device to be engaged with the punch while the latter is in non-centralized position to an extent where the teat projection 20 engages the face of the member 34, and as the punch is approximately adjusted to the point where it is centralized with the block member 22 the annular beveled seat surface 35^a is engaged by the teat projection 20 through 50 outward movement of the member 34 under pressure of the spring. During the centralizing adjustment of the punch with respect to the die, the punch is preferably so spaced with respect to the die that the member 34 is depressed and 55 the spring is compressed, substantially as shown 55 60 65 70 75

in Fig. 6, for the purpose of exerting axial spring pressure upon the several parts of the device.

To the block member 22 and its cover plate member 30, which together form a unitary part of the device, there is connected for relative lateral adjustment movement a cylindrical die-engaging disc member 40 provided diametrically at each side with holes 41-41, having counterbored recesses 42-42 at their outer ends and in which are engaged the smaller diameter screw-post members 43-43. These screw-post members have reduced threaded ends 44 engaged through the holes 32 of the plate member 30 and screwed into the threaded holes 25 of the block member, and are provided at their outer ends with shouldered heads 45 engaged in the recesses 42, these heads being of larger diameter than the holes 41 and of smaller diameter than the recesses 42. The distance from the shoulder of each of the recesses 42 to the inner surface of the block member 22 when the disc member 40 is flatly engaged against the plate member 30 corresponds exactly to the distance from the shoulder of the screw-post head 45 to the inner surface of the block member 22, so that while the disc 40 is in firm engagement with the plate member 30 relative transverse shifting movement of the block member with respect to the disc member will cause the screw-post head to move laterally in the recess 42, the clearance of the holes 41 with respect to the screw-post and the clearance of the recess 42 with respect to the head being sufficient to permit of substantial relative movement. The disc member 40 precisely corresponds in cylindrical size to the plate member 30 and the block member 22, so that when in exact centralized register, the cylindrical surfaces of two relatively adjustable parts of the device are continuous at all points, and hence, any eccentricity of the block member 22 with respect to the disc member is indicated by the formation of a ridge which can be readily detected by moving the finger or fingernail across the joint.

Centrally of the disc member 40 there is provided a cylindrical passage 46, extending inwardly to a counterbored cylindrical chamber 47, this chamber being preferably provided adjacent the inner face of the disc with a counterbored annular clearance recess 48. Within the passage 46 there is slidably engaged a cylindrical die-engaging plunger 49 provided at its inner end with an annular flange 50 engaging within the chamber 47 to limit the outward projection of the plunger. A spring 51 is engaged between a pocket 52 in the plunger and the dished recess 33 of the plate member 30 and exerts projecting pressure upon the plunger. The diameter of the plunger is predetermined to precisely fit within the passage 13 of the die 10 with a close sliding fit.

The axial clearance provided by the chamber 47 and the recess 33 is sufficient to permit the plunger to be pressed inwardly into the disc member 40 to a point where its outer end is flush with the outer flat surface of the disc member, so that in engaging the centering device with respect to the punch and die the plunger is depressed and the flat face of the disc member is firmly engaged with the flat face of the die in a non-centralized position, whereby the depressed plunger is retained in its depressed position. Thereupon the device may be shifted upon the face of the die to the point where the plunger 49 registers exactly with the passage 13, where-

upon it is automatically projected into engagement with the passage by the action of the spring 51, thus assuring an accurate sliding engagement of the plunger with the passage in exact parallelism without resort to manual forcing of the parts into engagement.

With the device thus engaged with the die, the punch is engaged with the member 34, the block member 22 shifting with respect to the disc member in the event that the punch is off-center, as indicated for instance by the dot-and-dash lines in Fig. 6. In centralizing the punch, the punch carriage 18 is preferably moved toward the die to the point where the member 34 is partially depressed, thus insuring that the parts of the centering device are firmly pressed together and are firmly pressed into relation with the punch and die in an axial direction under the pressure of the spring 37. With the parts in this position, the punch is adjusted to its centralized position, which is determined, for instance, as the block member is shifted from the off-center dot-and-dash line position shown in Fig. 6 to an exactly centralized position as shown by the full lines, and which position is determined accurately by passing the finger or fingernail over the joint between the cylindrical surfaces of the disc member 40 and the plate 30, the absence of any ridge indicating that the punch is axially aligned with the die.

In Figs. 7 to 11 there is illustrated a modified form of the invention, wherein one of the relatively transversely shiftable members of the gauge is adapted to be fitted into centralized relation within the die-holder and is axially engaged by the ejection stem or mandrel, while the other member of the gauge is adapted to be engaged in centralized relation by the punch.

The aligning gauge illustrated in Figs. 7 to 11 comprises an elongated cylindrical main body or block member 60, corresponding in diameter to the die 10, Figs. 1 and 2, which is removed from the passage 11 of the die-holder 12, during the aligning operation, to permit the member 60 to be inserted in the passage 12 in place thereof. The member 60 is provided with a cylindrical axial bore 61 provided at its forward end portion with a reduced diameter cylindrical portion 62. This bore is adapted to receive the ejection stem or mandrel 14, with its tapered end portion engaged with the annular shoulder edge at the inner end of the reduced portion 62, while its cylindrical portion fits exactly the outer end portion of the bore, so that when the member 60 is engaged within the die-holder the ejection stem or mandrel may be axially aligned with the die-holder, it being pointed out in this respect that the ejection stem, as shown in Figs. 1 and 2, is of smaller diameter than the passage 13 of the die, and therefore cannot be centralized by direct contact with the surface of the passage 13.

On the flat forward face of the member 60 there is secured for transverse shifting movement a disc member 63, having a cylindrical periphery which corresponds exactly to the cylindrical periphery of the member 60, and in axially aligned relation coincides therewith, this disc being provided centrally with a cylindrical aperture 64 provided at its outer end with an annular beveled surface 65 adapted to guide the punch into centralized engagement, the engagement being a line contact engagement with the annular edge at the inter-section of the cylindrical aperture 64 and the beveled surface 65.

Diametrically at each side of the aperture 64 the disc member is provided with cylindrical holes 66—66 which are engaged by retaining post structures secured to the forward end of the body member 60, there being limited transverse clearance between the holes and the post structures to permit transverse shifting of the disc member relatively to the body member 60. These post structures each comprise a cylindrical bushing 67, of a length corresponding exactly to the thickness of the disc member 63 and of smaller diameter than the hole 66, provided at its outer end with an annular flanged head portion 68, of larger diameter than the hole 66, and adapted to engage the outer surface of the disc 63 in surrounding relation to the hole 66, the bushing being secured rigidly to the member 60 by means of a screw 69 screwed into a threaded hole 70 in the member 60, its fillister head 71 being engaged in a counterbored recess 72 in the head end of the bushing.

The disc member is adapted to be transversely shifted in any direction with respect to the body member 60, as shown for instance in Fig. 10, to permit it to be engaged by the punch when the latter is out of axial alignment with the die-holder and ejection stem. Thereupon the punch is adjusted until the peripheral surfaces of the body member 60 and the disc member 63 are in exact register which may be accurately determined by moving the finger or fingernail across the joint between these members.

The forms of the invention illustrated in the drawings and described herein are typical and illustrative only, and it is evident that the invention is capable of embodiments in other forms, all falling within the scope of the appended claims, which are to be broadly construed.

What is claimed is:

1. In an alignment gauge for axially aligning a pair of cooperative tools, a member having a tool-engaging part movable axially in said member, a second member engaged with said first member, and having a tool-engaging part movable axially in said second member, one of said members being movable relatively to the other transversely of the axis of said tool-engaging parts, and registering means on said respective members adapted to register with each other in the axially aligned relation of said tool-engaging parts.

2. In an alignment gauge for axially aligning a pair of cooperative tools, a member having a spring engaged tool-engaging part movable axially in said member, and a second member engaged with said first member and having a spring engaged tool-engaging part movable axially in said second member, one of said members being movable relatively to the other transversely of the axis of said tool-engaging parts, the peripheral surfaces of said respective members corresponding and adapted to register with each other in the axially aligned relation of said tool-engaging parts.

3. In an alignment gauge for axially aligning a pair of cooperative tools one of which is a punch, a member having an axially disposed tool-engaging part, a second member engaged with said first member and having an axially disposed punch-engaging part having a punch seat receiving centering pocket, one of said members being movable relatively to the other transversely of the axis of said tool-engaging parts, and registering means on said respective members adapted to register with each other in the axially aligned relation of said tool-engaging parts.

aligned relation of said tool and punch-engaging parts.

4. In an alignment gauge for axially aligning a pair of cooperative tools, a member having a chamber and a tool-engaging part slideable axially in said chamber, a second member engaged with said first member and having a chamber and a tool-engaging part slideable axially in the second chamber, said members having planular inner ends engaged with each other and relatively movable transversely of the axis of said tool-engaging parts, circumferentially spaced connection means between said members permitting limited relative transverse movement, and registering means on said respective members registering with each other in the axially aligned relation of said centralized tool-engaging parts.

5. In an alignment gauge for axially aligning a pair of cooperative tools, a member having an axially disposed tool-engaging part at its outer end, a second member engaged with said first member and having an axially disposed tool-engaging part at its outer end, said members having planular inner ends engaged with each other and relatively movable transversely of the axis of said tool-engaging parts, a pair of headed posts at the inner end of one of said members extending axially and arranged diametrically at each side of the axis of said tool-engaging part, the other member having holes engaged by said posts and of a diameter permitting limited relative transverse movement, the post heads being of larger diameter than said holes to retain the connected relation of said members, and registering means on said respective members registering with each other in the axially aligned relation of said tool-engaging parts.

6. In an alignment gauge for axially aligning a pair of cooperative tools, a member having an axial passage, a tool-engaging part engaged in said passage, spring means exerting projecting pressure on said tool-engaging part, a second member engaged with said first member and having an axially disposed tool-engaging part, one of said members being movable relatively to the other transversely of the axis of said tool-engaging parts, and registering means on said respective members adapted to register with each other in the axially aligned relation of said tool-engaging parts.

7. In an alignment gauge for axially aligning a pair of cooperative tools, a member having an axial passage, a tool-engaging part engaged in said passage, spring means exerting protecting pressure on said tool-engaging part, a second member engaged with said first member having an axial passage, a tool-engaging part engaged in said passage, spring means exerting projecting pressure on said last-mentioned tool-engaging part, one of said members being movable relatively to the other transversely of the axis of said tool-engaging parts, and registering means on said respective members adapted to register with each other in the axially aligned relation of said tool-engaging parts.

8. In an alignment gauge for axially aligning a pair of cooperative tools one of which is a die, a member having an axial passage, a tool-engaging part engaged in said passage and depressible into flush relation with the outer side of said member, spring means exerting projecting pressure on said tool-engaging part to engage it in said die, a second member engaged with said first member and having an axially disposed tool-engaging part, one of said members being

movable relatively to the other transversely of the axis of said tool-engaging parts, and registering means on said respective members adapted to register with each other in the axially aligned relation of said tool-engaging parts.

9. In an alignment gauge for axially aligning a pair of cooperative tools, one of which is a work-piece-carrying mandrel, a member having an axially disposed passage adapted to be engaged by said mandrel, a second member engaged with said first member, and having an axially disposed tool-engaging part, one of said members being movable relatively to the other transversely of the axis of said members, and registering means on said respective members adapted to register with each other in the axially aligned relation of said members.

10. In an alignment gauge for axially aligning a pair of cooperative tools, one of which is a tapered work-piece-carrying mandrel, a member having an axially disposed passage adapted to be engaged by said mandrel including a cylindrical portion, and a reduced diameter cylindrical portion having an annular shoulder between them adapted to have line contact with

the tapered surface of said mandrel, and a second member engaged with said first member and having an axially disposed tool-engaging part, one of said members being movable relatively to the other transversely of the axis of said members, and registering means on said respective members adapted to register with each other in the axially aligned relation of said members.

11. In an alignment gauge for axially aligning a pair of cooperative tools, one of which is a die-holder having a die-receiving passage and a work-piece-carrying mandrel, a body member having a tool-engaging part corresponding in shape to the die fitting said die-holder and engageable in said die-holder passage, said body member having an axially disposed passage adapted to be engaged by said mandrel, a second member engaged with said first member and having an axially disposed tool-engaging part, one of said members being movable relatively to the other transversely of the axis of said members, and registering means on said respective members adapted to register with each other in the axially aligned relation of said members.

25 ROLAND SMITH PAYNE.
